ATTYS.

UNITED STATES PATENT OFFICE.

ELMER A. POUND, OF VENICE, CALIFORNIA.

AUTOMATIC TRAFFIC-REGULATOR.

1,240,090.

Specification of Letters Patent. Patented Sept. 11, 1917.

Application filed July 11, 1916. Serial No. 108,582.

To all whom it may concern:

Be it known that I, ELMER A. POUND, a citizen of the United States, residing at Venice, in the county of Los Angeles and 5 State of California, have invented new and useful Improvements in Automatic Traffic-Regulators, of which the following is a specification.

This invention relates to a traffic regulator and particularly pertains to automatic means for regulating the traffic at street crossings in large cities.

It is an object of this invention to provide automatic means which will constantly 15 operate to alternately direct the movement of pedestrians and vehicles in crossing street intersections.

Another object is to provide simple timing mechanism which will act in a positive 20 manner to actuate the regulator at given intervals to change the direction of traffic movement.

Another object is to provide means which act automatically to illuminate the signal 25 when in its signaling position.

It is a further object to provide a traffic regulator which is constructed of few parts not liable to become disordered and which may be inexpensively manufactured.

30 Other objects will appear hereinafter.

The invention is illustrated in the accompanying drawings in which:

Figure 1 is a view in perspective illustrating the traffic regulator in its operative position and disclosing the indicia upon the 35 semaphore block.

Fig. 2 is a view in vertical section as seen on the line 2—2 of Fig. 1 and as illustrating the arrangement of the semaphore block 40 mounting within the base.

Fig. 3 is a view in vertical section as seen on the line 3—3 of Fig. 2 and particularly discloses the timing mechanism and its motor drive.

45 Fig. 4 is a view in horizontal section as seen on the line 4—4 of Fig. 3 and illustrates the actuating mechanism by which the semaphore block is rotated.

Fig. 5 is a view in horizontal section as 50 seen on the line 5—5 of Fig. 2 and illustrates the electrical contact rings by which the semaphore block is illuminated.

Fig. 6 is a view in horizontal section as seen on the line 6—6 of Fig. 2 and in the direction of the arrows. 55

Fig. 7 is a view in vertical section as seen on the line 7—7 of Fig. 3 and illustrates the cam face arrangement by which the semaphore block is lifted out of contact with the electric illuminating circuit. 60

Fig. 8 is a view in plan illustrating the square plate used to rotate the semaphore by means of the semaphore actuating levers.

Referring to the drawings more particularly, 10 indicates a base which is preferably square in shape and which is adapted to rest upon the pavement at the center of street intersections. The base is hollow and contains actuating mechanism by which a semaphore block 11 is rotated and illuminated. The semaphore block is formed with a vertically extending frame which is rectangular in shape and has mounted within each of its sides, translucent plates upon which suitable indicia are inscribed. 70 As shown in the drawings, diametrically opposite sides bear the word "Stop" arranged vertically, one letter below the other. The two remaining plates have the word "Open" inscribed upon them. These inscriptions indicate when the traffic is to move and when to remain still. 75

The semaphore block is actuated by means of a motor 12 which is fitted with a worm gear 13 adapted to mesh with a worm wheel 85 14. The worm wheel has a suitable spur gear mounted upon it which engages one of a train of gears. In the drawings, the train consists of large diametered gears 15 and 16 and small gears 17 and 18. These gears 90 move in synchronism and produce intermittent rotation of the semaphore block. This movement is produced by means of an engaging pin 19 which is secured upon the face of the gear 16 and is thus brought into 95 engagement with the end of a rocker arm 20 once in each revolution of the gear 16. The rocker arm is pivoted upon the bottom of the base 10 by means of a pivot pin 21 and extends outwardly across the bottom of the 100 base. The outer end of said rocker arm is connected by a pitman rod 22 to a vertically disposed shifting arm 23 which is suitably mounted for universal movement within a

mounting 24 secured to the floor of the base. A coil spring 25 is provided to constantly exert power to rotate the rocker arm 20 in the direction of the arrow —*a*— and another coil spring 26 is secured to the shifting arm 23 and normally draws it in the direction indicated by the arrow —*b*—.

The shifting arm is adapted to engage one of a series of notches 27—30 inclusive 10 formed adjacent the corners of a square rotating plate 31 secured to a vertically disposed semaphore shaft 32 upon which is mounted the semaphore block. The rocker arm 20 and the pitman rod 22 are so correlated 15 that they swing the shifting lever the proper amount of movement to rotate the plate 31 one quarter of its revolution and thereby change the position of the semaphore block so that the indicia exposed to 20 the traffic upon the various street corners will be reversed at each quarter turn of the semaphore block.

In order to attract the attention of the traveling public to the regulator the semaphore block is intermittently illuminated by 25 suitable incandescent lamps 33 which are arranged within the semaphore block and which are supplied with an electric current which is delivered to conductor rings 34 and 30 35 by electrical conductors 36 and 37. These rings are insulated from each other and lie concentric to each other upon a plate 38 mounted upon the base and around the semaphore shaft 32. A series of four rollers 35 39—42 inclusive are secured upon the under face of the semaphore block and are arranged in pairs diametrically opposite each other and upon circles whose diameters are similar to the diameters of the rings 34 and 40 35. These rollers are contact rollers and, when bearing upon the rings 34 and 35, complete circuits to the lights within the semaphore block. The intermittent illumination of these lights is effected by a face cam 43 45 which is formed within the bottom of a thrust bearing 44 adapted to receive the lower end of the semaphore shaft 32 and carry the complete weight of the semaphore block. The face cam is formed with four 50 swells which are arranged at right angles to each other and which engage a similar face upon the end of the shaft 32. This combination of cam faces acts to raise and lower the semaphore block at each quarter turn and 55 thus relieves the rollers 39—42 inclusive from contact with the conductor rings 34 and 35.

The entire device in operation is actuated by the electric motor 12 which is supplied 60 with a constant flow of current which permits it to run continuously. The train of gears connecting with the motor is designed to reduce the speed of rotation of the gear 16 to suitably time it in its rotation of the 65 semaphore block. Observation has proven

that the movement of traffic in one direction requires approximately thirty seconds and the device here shown is timed to approximately that speed. However, individual traffic conditions will govern this matter. 70 When the gear 16 is rotated, its pin 19 will engage the engageable end of the rocker arm 20 and swing it in the direction indicated by the arrow —*c*—. This movement will draw the pitman rod and consequently the shifting 75 lever 23 so that the semaphore plate will be rotated a quarter of a revolution. Simultaneously, the semaphore will be vertically reciprocated upon the cam 43 and will, during the transition from one position to the other, 80 discontinue the illumination within the semaphore block. However, the cam will permit the rollers to become seated upon the conductor rings at the time the semaphore block ceases to move and will thus cause the 85 block to be illuminated during the interval it remains stationary.

It will thus be seen that the traffic regulator herein illustrated and described is simple in its operation, will require but slight 90 attention to maintain it in working order, and that it is provided with positive means to intermittently illuminate it to more effectively attract attention and cause the 95 pedestrians to be guided thereby. 95

Various changes in the construction and arrangement of parts of my traffic regulator may be made by those skilled in the art without departing from the spirit of my invention as defined in the appended claims. 100

I claim:

1. A traffic regulator, comprising a vertically disposed semaphore block, indicia inscribed upon the sides of said semaphore block, means whereby said block may be intermittently and regularly rotated a given portion of a revolution, means for illuminating the semaphore block, and means whereby the semaphore block may be reciprocated while rotating to discontinue the illumination therein. 105

2. A traffic regulator comprising a supporting base, a rotatable vertical shaft mounted thereon, a semaphore block mounted fast to said shaft, timing gears constantly driven within said base, means operatively connected to said gears for rotating said shaft a quarter revolution in the same direction at regular intervals, means for illuminating said block, and means whereby the illumination may be discontinued during the rotation of said shaft, said means including a contact point fast to said base and a contact point fast to said block adapted to engage said first-named contact point when said block is at rest and to be disconnected when said block is rotated. 115

3. A traffic regulator comprising a supporting base, a rotatable vertical shaft supported thereby, a rectangular vertical sema- 120

phore block fast to said shaft, traffic regulating indicia carried by said block, means for imparting a quarter revolution to said shaft at regular intervals, said means including
5 reducing gears operatively connected therewith, a toothed plate fast to said shaft, a pin on one of said gears, a lever intermit-

tently operated by said pin, and operatively connected to said plate, and resilient means restoring said lever to its original position 10 after its engagement with said pin.

In testimony whereof I have signed my name to this specification.

ELMER A. POUND.
